United States Patent Office

Des. 195,897
Patented Aug. 6, 1963

195,897

BOTTLE

Donald M. Kitterman, Kansas City, Kans., assignor, by
mesne assignments, to Pacific Industries, Inc., San Fran-
cisco, Calif., a corporation of California

Filed Oct. 8, 1962, Ser. No. 72,019

Term of patent 14 years

(Cl. D58—6)

Fig. 1.

Fig. 2.

Fig. 3.

Fig. 4.

Fig. 5.

FIG. 1 is a side elevational view of a bottle embodying my design, the opposed side being a mirror image of the side illustrated.

FIG. 2 is an end elevation view thereof, the opposed end being a mirror image of the end illustrated.

FIG. 3 is a bottom view thereof.

FIG. 4 is a top view thereof.

FIG. 5 is a fragmentary vertical sectional view taken through the center thereof.

I claim:

The ornamental design for a bottle, as shown and described.
